Willis Harold Miller, Dallas, Tex.

Application August 19, 1944, Serial No. 114,944

Term of patent 14 years

(Cl. D48—16)

To all whom it may concern:

Be it known that I, Willis Harold Miller, a citizen of the United States, residing at Dallas, in the county of Dallas and State of Texas, have invented a new, original, and ornamental Design for a Shade for a Lamp or Similar Article, of which the following is a specification, reference being had to the accompanying drawing forming part thereof.

Fig. 1 is a front or face elevational view of a shade for a lamp, showing my new design;
Fig. 2 is a side elevational view thereof.

I claim:

The ornamental design for a shade for a lamp or similar article, as shown.

WILLIS HAROLD MILLER.
